Patented Dec. 8, 1914.

UNITED STATES PATENT OFFICE.

DANIEL B. COLLINS, OF FARGO, NORTH DAKOTA.

SCREEN.

1,120,601.

Specification of Letters Patent.

Patented Dec. 8, 1914.

Application filed July 5, 1913. Serial No. 777,575.

To all whom it may concern:

Be it known that I, DANIEL B. COLLINS, a citizen of the United States, residing at Fargo, in the county of Cass and State of North Dakota, have invented certain new and useful Improvements in Screens, of which the following is a specification, reference being had to the accompanying drawings.

10 This invention relates to new and useful improvements in screens and more particularly to window and door screens, the object of this invention being to provide an improved device of this character which 15 will permit flies and other insects to escape from the interior of the house but will prevent them from returning.

Another object of the invention is to provide a device of the above character which 20 will possess advantages in points of efficiency and durability, is inexpensive of manufacture and at the same time is simple in construction and operation.

With the above and other objects in view, 25 the invention consists in the novel features of construction and the combination and arrangement of parts to be hereinafter more fully described, pointed out in the claim and shown in the accompanying 30 drawings, in which—

Figure 1 is an elevation of a screen constructed in accordance with my invention; Fig. 2 is a transverse sectional view; and Fig. 3 is a detail transverse sectional view.

35 Referring more particularly to the drawings, 1 indicates the longitudinal sides of the frame, which are suitably connected at their ends by means of the transverse cross pieces 2. Arranged upon the outer sides of 40 the pieces 1 and 2 is a wire screen 3, the edges of which are securely held in position by means of the cleats 4 arranged upon the side and end pieces and secured thereto by means of the screws or nails 5. The longitudinal side pieces 1 are provided adjacent 45 one end with the offsets 6, upon which are arranged the ends of a second screen wire 7, the upper edge of the second screen wire 7, being arranged across the upper end piece 50 2, said screen being held securely in place by means of the headed pins 8. The lower edge of the second screen wire 7 is arranged in spaced relation with the outer screen 3 and secured thereto by means of the tubular spacing member 9, said member being 55 provided at its ends with the spurs 10

adapted to engage in the meshes of the screen wire to securely hold the same in position.

The upper end of the frame includes a 60 plurality of separable blocks, the end blocks being substantially rectangular in form and provided with the inner inclined end portion 11, the purpose of which will be hereinafter more fully set forth. The blocks 65 12 which are arranged between the end blocks are substantially triangular in form and the spaces between said blocks form suitable outlet openings which are adapted to communicate with the openings 14 70 formed in the top plate 15, which is arranged across the upper end of the frame. It will be noted that the inclined walls 11 of the end blocks form one of the side walls of one of the outlet openings, one of the 75 triangular blocks forming the other side wall of the outlet opening. The openings 14 are struck out from the metal plate 15, the struck out portions being adapted to provide suitable spurs 16, which are circum- 80 larly arranged around the openings 14. It will be apparent that the insects crawling up the inner side of the screen 3 will pass beneath the second screen 7 and upwardly through the openings 13 and 14, passing 85 out between the spur members 16. It will also be apparent that it will be almost im- 90 possible for the insects to pass down through the openings 14 on account of the spurs 16.

From the above description taken in connection with the accompanying drawings, it will be readily apparent that I have provided a new and useful screen, which is adapted for application to windows and 95 doors whereby the flies and other insects will readily pass from the interior to the exterior, but at the same time will not be permitted to pass back to the interior. It will also be apparent that the device in 100 itself is extremely simple in construction and can be manufactured at a comparatively low cost.

While I have shown and described my invention applied to the ordinary window 105 screen, it will be readily understood that the same may be applied and used equally as well upon screen doors and the like.

While I have shown and described the preferred form of my invention, it will be 110 obvious that various changes in the details of construction and in the proportions may

be resorted to for successfully carrying my invention into practice without sacrificing any of the novel features or departing from the scope of the appended claim.

5 What I claim is:—

In a screen, the combination of a frame comprising side pieces, end pieces connecting said side pieces, a screen arranged upon the outer sides of said side and end pieces, 10 said side pieces being provided adjacent one end with offsets, a second screen wire arranged upon said offsets and in spaced relation with the first screen, a tubular member having spur members formed upon 15 each end thereof and adapted to engage

within said screen wires to hold the same in position, one of said end pieces being provided with exits, a plate arranged across one end of the frame and having openings communicating with said exits, 20 the struck out portions forming said openings providing spurs circularly arranged around said openings to prevent the insects from entering through said openings.

In testimony whereof I hereunto affix my 25 signature in the presence of two witnesses.

DANIEL B. COLLINS.

Witnesses:

JOHN G. PFEFFER,
FRED RUFFNER.
